UNITED STATES PATENT OFFICE.

EDWARD E. WILSON, OF CLEVELAND, OHIO, ASSIGNOR TO THE WILSON DISPLAYO-
TYPE MACHINE CO., OF CLEVELAND, OHIO, A CORPORATION OF OHIO.

TYPECASTING AND LINE-FORMING MACHINE.

1,370,676.

Specification of Letters Patent.

Patented Mar. 8, 1921.

Application filed February 10, 1920. Serial No. 357,565.

To all whom it may concern:

Be it known that I, EDWARD E. WILSON, a citizen of the United States, residing at Cleveland, in the county of Cuyahoga and State of Ohio, have invented certain new and useful Improvements in Typecasting and Line-Forming Machines, of which the following is a specification.

This invention relates to a new and novel improvement in type casting and line forming machine and has for its object to provide a means for carrying a large number of different sizes and face of type or type matrices in one machine, and for bringing these different type or type matrices into position for printing or casting and for the purpose of forming type letters to be used in printing.

Further objects of the invention are to provide a plurality of holders in which type or type matrices may be carried and independently used and stored in a convenient manner to be delivered to a central printing or casting point, a print or cast being made therefrom and the type or matrix delivered back into the container, magazine or rack.

Still further objects of the invention are in the provision of means for locating the proper carrier in registry with the printing or casting point, means for disposing of the printed or formed type face in a convenient and efficient manner, the provision of a suitable mechanism for controlling the proper movement of the carriers in a rapid and efficient manner and the provision of a machine which will be simple and durable, nominal in cost and capable of serving wide usage.

To this end the invention consists in the certain construction and combination of parts which may best be described in connection with the accompanying drawings and particularly pointed out in the following specification and claims.

Reference being had to the accompanying drawings wherein like reference numerals designate similar parts of reference throughout the various views, Figure 1 is a side elevation of the machine; Fig. 2 is a plan view drawn to a large scale; Fig. 3 is a horizontal section taken on the line 3—3 of Fig. 1; Fig. 4 is a transverse section on the line 4—4 of Fig. 1; Fig. 5 is a similar section as indicated by the line 5—5 of Fig. 6; Fig. 6

is a sectional detail on the line 6—6 of Fig. 5; Fig. 7 is a similar detail on the line 7—7 of Fig. 4; Figs. 8 and 9 are sectional details of the matrix clamps; Fig. 10 is a perspective of the type stick; Figs. 11 and 12 are sectional details corresponding to the lines 11—11 of Fig. 2 and 12—12 of Fig. 11; Fig. 13 is a perspective view of the matrix carrier one of the matrices being partially removed; Fig. 14 is a perspective view of a type letter; Fig. 15 is a perspective view of a type face as it emerges in its completed form from the machine; Fig. 16 is a detail in perspective of the mold disk or wheel.

The invention consists of a table 1 supported upon legs 2 at a convenient height for operating. On the top of the table and at each end thereof are supported front and back frames 3 and 4, respectively. These frames are secured equidistant from each other by being bolted at the bottom to the table top and at the top by cross bars 5, and are each provided with an overhanging portion 6 which permits a cage or frame 7 to slide longitudinally back and forth upon tracks 8 which extend at right angles to and are made as a part of the frames 3 and 4. The cage 7 is composed of end and side members 9 and 10 respectively and is permitted to freely move upon the aforesaid tracks upon anti-friction rollers 11 secured to the sides 10 and said cage supports the type or matrix carriers which will now be described.

As previously stated, the carriers of the type or type matrices must be so constructed and stored as to permit of independent use and positioning with respect to a central casting point. With this end in view I have designed a boxed carrier 15 provided with separate compartments 16 in which are placed the type or type matrices, and said type or type matrices each comprise a rectangular plate 17 upon one end of which is stamped or electrotyped a type 18 or type matrix. The plates 17 are retained in their respective compartments 16 by a cover plate 20, the edges of which are dove-tailed to occupy like recesses 21 in the carrier 15. The carrier 15 is further provided with interlocking hinge members 22 and 23 at the top and bottom, so that they may be assembled in the form of a bar or chain of carriers, each bar containing two or more carriers, and as shown in the drawings, Figs.

4 and 5, the bar or chain comprises five carriers and each carrier may confine a series of type or type matrices or characters of a different font. At the top said carriers are secured by means of their hinge joint to a bar-carrying plate 25 and said plate is provided with ears or lugs 26, which rest upon the aforesaid tracks 8. These lugs 26 may be provided with anti-friction rollers to facilitate their free movement upon said tracks, but this is optional and therefore has not been illustrated, and, as clearly illustrated, a plurality of said plates are confined within the frames of the cage 7.

15 The aforesaid frames 3 and 4 are provided at their middle with vertical flanged slideways 28 which terminate on a plane with the top surface of the tracks 8 and extend downwardly to a point just above the casting or mold wheel, which will be hereinafter described, and a pair of sliding conveyers 30 are adapted to move within each slideway, which conveyers are provided with studs 32 which project outside the limits of the frames 3 and 4 and are engaged by the slotted ends of a pair of levers 35 which are located outside of the frames 3 and 4 and are pivoted at their ends upon a shaft 36 which has a bearing in and extends between and through the foresaid frames, and said levers are adapted to be operated by links 37 pivotally secured at one end to the middle of the levers 35. These links are provided at the opposite end with slots 38 in which are engaged a second pair of levers 39 pivoted upon a shaft 40 which extends through and has bearings in the aforementioned frames 3 and 4. The aforementioned levers 39 are provided with a lost motion connection with the levers 37 for a purpose to be hereinafter described, and are in turn each operated by a link 41 having connection with a crank arm 42 securely fixed upon a third shaft 43, which has bearing in the frames 3 and 4, and which is manually operated by a crank 44 provided with an operating handle 45. It is evident that upon motion being given to the crank 44 and a connection established after a predetermined time with the levers 35, said motion causes the conveyers to be moved vertically within the slideways aforementioned, and the method of selecting the proper bar of matrix carriers preliminary to this movement will now be described.

55 The hereinbefore referred to cage 7 has secured to it a rack 50 by means of supporting members 51 which are secured thereto and which extend beyond the outside limits of the frame 3 and said rack is engaged by a spur gear 53 mounted upon a shaft 54 having suitable bearing in the overhanging portion 6 of the frames 3 and 4. This shaft has also secured thereon a bevel pinion 55 which meshes with a like pinion 56 upon a substantially vertical shaft 57, and said shaft is driven through a like pair of bevel gears 58 by a crank 59. Said gears 58 are suitably mounted in a bearing member 60 supported upon the top of the table 1. The shaft 61 upon which the crank handle 59 is mounted also has secured thereto a disk 62 and said disk is provided with a series of graduations about its outer circumference which are marked according to the character that it is desired to select. In this manner the crank 59 is rotated until the indicating finger 65 points out the character desired, motion being transmitted through the gearing and rack before mentioned to the cage 7, and the assembly of matrix bars are caused to move longitudinally upon the tracks 8 until the proper bar of matrices is in alinement with the slideways 28. At this time the lugs 26 rest upon the top surface of the conveyers 30 and upon motion being transmitted to the levers 35 the bar or chain of matrices is caused to descend vertically with the conveyers within the slideways 28.

After determining the proper character or letter it is desired to cast, it is next necessary to determine the proper font or form of that same letter or character, as it will be remembered that each bar of matrices will carry a plurality of different fonts. This is accomplished by means to limit the downward vertical movement of said bar, and consists of a stop 70 slidably mounted in alinement with the slideways 28 and substantially at the middle of the table 1, and said stop is operated by a rack 71 having engagement with a spur gear 72 driven by means of an operating wheel 73. A plurality of graduations 74 upon the face of the stop upon coming in alinement respectively with the top plane of the table will determine the exact font of type coming in registry with the proper point of the casting apparatus as will appear more clearly hereinafter.

It will be obvious that after the proper matrix has been located definitely with respect to the proper casting position it is essential that the same be effectively clamped thereagainst, and means for accomplishing this result consists of a swinging carrier clamp or vise indicated generally at 110 and illustrated in detail in Figs. 8 and 9. Said vise is pivoted at its lower end upon an arbor 111 securely mounted in a suitable bracket formed as part of the frame 4 and is adapted to be swung into and out of engagement with the carrier 15 by a pair of horizontal arms 112 secured at one end to said vise by means of a shaft 115 which extends transversely of the frames 3 and 4 and is securely fixed to said vise by means of the brackets 116, and said arms are given a reciprocatory movement by cams 118 the extreme outer ends of the shaft 40 engaging a pair of rollers 118 secured to the ends of the arms 112. As clearly indicated in Fig. 1

the arms 112 are slotted at one end to permit bearing to be had upon the shaft 40, thus confining them in such a manner as to keep them in the proper engagement whereby motion may be transmitted thereto. The vise or clamp 110 is provided at its upper end with a central partition 120 and at each end thereof with movable members 121. The members 121 are normally thrust outwardly or away from the partition 120 by springs 122 and at the time of clamping the carrier in place are adapted to move inwardly or toward the partition 120, so as to effectively clamp the carrier in the space 124, 15 by the beveled edges 125 engaging the beveled surfaces 126 of wedge blocks 127 secured to and supported by the frames 3 and 4. This movement takes place only when the vise is thrust in a direction toward the 20 casting or mold wheel. Upon referring particularly to Fig. 7, it will be seen that the clamp further supports, by means of a pair of arms 130, a strap member 131 which is so positioned as to engage the opposite side of 25 the carrier 15 to that which is engaged by the clamp 110. This is provided for the purpose of freeing the matrix from the formed type face after same has been cast and the action takes place simultaneously with the 30 freeing movement of the clamp from the carrier 15.

Upon reference particularly to Figs. 4 and 5 it will be seen that two separate bars of carriers depend from the plate 25 and to 35 properly position the same with respect to the proper casting position I provide an index 135 supported in such a manner by the side frames 3 and 4 as to separate them the proper distance preliminary to their 40 positioning themselves within the clamp 110.

The casting apparatus comprises a casting or mold wheel 75 in the form of a steel disk provided with a hub portion 76 which permits it to be mounted upon the end of a 45 horizontal shaft 77 located between the frames 3 and 4 and supported by a bearing 78 secured to the table 1. The wheel 75 is further provided with a plurality of rows of rectangular tangential openings 80 and with 50 a second series of openings 81 spaced 90 degrees apart. The aforementioned openings 80 allow the molten metal to enter the matrices and form the stem of the type face as will appear more clearly hereinafter.

55 The wheel is intermittently rotated one-quarter turn upon each selection of type face and this is accomplished by means of a bevel pinion 85, Fig. 3, loosely secured upon the opposite end of the shaft 77, and said pinion has formed thereon a hub portion 86 provided with ratchet teeth 87 which are engaged by a ratchet collar 88 splined to said shaft, and normally held in engagement with the teeth 87 by a spring 89 interposed 60 between said collar and the bearing 78. The

bevel pinion 85 is rotated at the proper time by means of a gear segment 90 provided with skew teeth 91 and is fixed to the shaft 40.

As before stated, the openings 80 in the mold wheel 75 form the stem of the type 70 faces, and as the wheel rotates through one-quarter turn it carries with it the formed type face. It is therefore obvious that ejecting means must be provided to remove the formed type faces from the mold wheel, and 75 said means consists of a plurality of ejector rods 95 equal in number to the openings 80 and which are slidably mounted within an extension bearing 96 formed as part of the main bearing 78 and secured at one end to a 80 head 97 which has pivotally connected thereto an arm 98 receiving its motion through a crank 99 secured upon the shaft 43. The slotted connection at 99^a between said arm 98 and crank 99 is so constructed as to permit of considerable lost motion being had therebetween. The aforesaid rods 95 are further provided with reduced ends 100 which enter the openings 80 in the mold wheel and thereby effectively eject the 90 formed type face. It is further necessary to provide a means for positioning the mold wheel in an exact relation to the type matrices and this is accomplished by an adjuster rod 101 provided at one end with a 95 reduced portion 102 which enters one of the openings 81 in said mold wheel and has its opposite end secured to the head 97 hereinbefore referred to.

Means for supplying molten metal to the 100 rear of the mold wheel and through the openings 80 comprises a metal pot, pump and heating appliance which is not shown in detail in the drawings, as there are many different appliances of this class and the selection of these parts were left to be adapted to the needs of the machine, therefore the metal pot only is shown and is indicated at 140, for holding the molten metal, constructed with a jacket similar to those used in 105 other type or slug casting machines and with a nozzle 141 opening directly upon the rear of the aforementioned mold wheel, the nozzle being so constructed as to form a shut-off back ground for those openings 80 of the 110 mold wheel which are not in use. The metal pot 140 is pivoted to the base plate at 142 in such a manner that the swing of the said pot will carry the nozzle over and directly in 115 line with the proper opening in the mold wheel. The movement of said metal pot may be controlled by means of suitable links or levers in any convenient manner to swing the same and in order to place the nozzle in the proper position. The foregoing constructions are well known to the art and 120 therefore require no further illustration or description.

A plurality of openings 80 in each set is provided, for the following reasons; the cage

or rack (7) contains two series of matrix carriages suspended therefrom (one series is for lower case letters and the other is for capital letters, the two figures and marks for all fonts being divided equally in the two series of mat carriages) see Fig. 4. In the operation of the machine, the metal pot is provided and placed in such manner as to swing over from the capital letter and back to the lower case letter, the metal pot being provided with a solid flat surface mouthpiece with only one orifice for the metal to be forced through by the action of the pump located on the inside of the metal pot. When the letter is casting, this flat surface forms a back wall for the holes in the disk except the hole which comes in alignment with the opening in the metal pot mouthpiece. When the mouthpiece is clamped against the disk on one side of the wheel, the matrix carriage is clamped against the other side with the letter to be cast resting in direct alignment with the hole in the mouthpiece. The metal is forced through the orifice of the mouthpiece, into and through the hole in the disk, and into the matrix where it fills the matrix, thus forming the letter. Should it happen to be a thin letter to be cast there would be but one stem at the back of the letter, but should it be a wide letter, the metal being forced over to the edge of the matrix, it enters the other one or two holes in the disk and thus forms one or two or more stems at the back of the letter. This is for the purpose of securing the letter more firmly to the slug when the slug is cast onto the letter, as the wide letter would have one or two or more stems around which the base slug would be cast. Then in casting the lower case letters the metal pot mouthpiece is shifted back so as to bring the orifice in the mouthpiece into alignment with the fourth hole from the right. It will be noticed that all six of the ejector rods work simultaneously immediately after the wheel adjuster (101—102) thus entering all holes in the disk and ejecting the letter, whether it be in the first three holes or the second three holes of the mold block.

As before described the formed type faces are ejected from the mold wheel by the ejector rods 95, and in order to keep the same in their successive order a type stick or magazine indicated generally at 150 is provided.

Said type stick consists of a face plate 151 provided with a vertical slot 152 and secured to a back plate 153. A second plate which shall be termed the letter slide 154 is mounted directly in back of the plate 151 and spaced from the back 153 a distance equal to the thickness of the type face, and said slide is permitted a vertical movement between guideways 155 carried by the back 153 so that when a letter is cast in the opening indicated at 80° the slide may be moved

up or down by the handle thereon to allow the slot 156 in the slide 154 to adjust itself to the arc defined by the opening 80° at one-quarter rotation of the mold wheel. The formed type face is then ejected with the type face between the back 153 and the slide 154 with the stem projecting through the vertical slot 156. This type stick is pivotally mounted at the bottom end as indicated at 160 to a suitable bracket 161 carried by the table top and when the type stick has become filled to its capacity the same is tipped forward and the type emptied into a channeled or grooved galley for further operation.

In Fig. 15 I have illustrated in detail the formed type face which consists of a body portion 170 provided with a stem 171.

With the parts constructed as described and the metal in the metal pot being in condition the first operation is the location of the proper font desired by turning the hand wheel 73. The operator then with his left hand turns handle 59 until the letter desired comes directly in line with pointer 65. Then with the right hand he throws crank 44 over to right, this brings the arms 35 down carrying the bar or chain in the conveyers 30 down to carrier stop 70, leaving the font desired directly in line with the nozzle 141 of the metal pot 140 and one of the openings 80 in the mold disk or wheel 75. This movement also turns shaft 40 which throws the clamp arms 112 toward the right, thus clamping the mat carrier 15 snugly against the mold disk or wheel 75, and at the same time it releases the plunger in the metal pot, this causing the molten metal to be forced upward and into and through the nozzle 141 of the metal pot 140 and into the mold disk 75. This movement also throws forward the mold wheel adjuster 101 and the ejector rods 95 thus securing the mold disk rigidly in position and ejecting any letter which may be in the preceding openings in the mold disk. After the operator has thrown the handle 44 to the right as far as it will go he brings it back to the left. This movement brings the mold disk 101 and ejectors 95 back into position, at the same time it brings the metal pot plunger back into position, and also raises conveyer arms 35, this carrying the bar of mat carriers back into the rack and at the same time gear segment 90 fixed to shaft 40, engages the ratchet pinion 85 upon the main shaft 77, turning said shaft and bringing the cast letter into position for ejection and also brings another series of openings into position to be in line for another mat carrier. Another similar operation ejects the letter just cast and the stem of the letter slides down the opening in the type stick. The operations are continued until the type stick is filled. The type stick

is then tipped forward and the type emptied by sliding it out of type stick slide and into a channeled or grooved galley where it is properly spaced and justified. It is then carried to a slug caster where the type high slugs are cast, thus forming a type high printing slug, which is ready for use, by underlaying the letters with slug-high metal bases or quads or slugs.

10 I claim:

1. In a type casting machine, the combination of a track, a frame slidable back and forth thereon, a plurality of matrix carriers supported by said frame, guideways 15 communicating with said track and provided with conveyers, means to register any one of the carriers with said conveyers, and means to operate the conveyers to shift the selected carrier from the frame to casting

20 position and return.

2. In a type casting machine, the combination of a track, a frame slidable back and forth thereon, a set of matrix carriers mounted upon the frame, a guideway leading from the track to casting position, a pair of conveyers movable in the guideway at opposite sides thereof and adapted to engage a selected matrix carrier, means to shift the frame back and forth, and means 25 to shift the conveyers from the track to casting position and return.

3. In a type casting machine, the combination of an upper horizontal track, having openings in the rails thereof, a pair of 35 slideways leading from said openings to casting position, a pair of conveyers movable up and down in said slideways and adapted to register with said rails when in raised position, a frame slidable back and forth on said track, a set of matrix carriers mounted in said frame and adapted to be selectively registered with said conveyers, and means to raise and lower the conveyers, to carry the selected matrix carrier to casting 40 position and return.

4. In a type casting machine, the combination of a horizontal track, a frame slidable back and forth thereon, a set of matrix carriers mounted in said frame, a pair of 50 slideways communicating with said track and depending therefrom to a casting position, a pair of conveyers movable up and down in said slideways and adapted to support a selected matrix carrier and lower the same to casting position and return, and means to raise and lower the conveyers.

5. In a type casting machine, the combination of a horizontal track, a frame slidable back and forth thereon, a set of matrix 60 carriers mounted in said frame, a pair of slideways communicating with said track and depending therefrom to a casting position, a pair of conveyers movable up and down in said slideways and adapted to support a selected matrix carrier and lower the

same to casting position and return, and means to raise and lower the conveyers, said means including a pair of levers operatively connected to the conveyers.

6. In a type casting machine, the combination of a horizontal track having openings through which a matrix carrier may drop, a guideway leading from said openings, a frame, a set of matrix carriers mounted in said frame, the frame being 70 slidable back and forth on the track to register a selected matrix carrier with said openings, a pair of conveyers mounted in said slideway and movable up and down therein and constructed to engage and raise 80 and lower the selected matrix carrier, means to operate the conveyers to shift the matrix carrier to casting position and return.

7. In a type casting machine, the combination of a track, a frame slidable back 85 and forth on said track, a set of matrix carriers mounted in said frame, means to move a selected matrix carrier from said frame to casting position and return, and means to move the frame, including a rack attached 90 to the frame, a pinion engaging the rack, a shaft geared to the pinion, a crank to turn the shaft, and an indicating disk carried by the shaft and provided with marks to indicate a selected matrix carrier. 95

8. In a type casting machine, a matrix carrier comprising a plate having grooves therein adapted to receive matrices, and a removable cover engaging said plate and extending over the grooves to confine the 100 matrices therein.

9. In a type casting machine, the combination with a top plate provided with projections adapted to slide along a track, of a series of matrix carriers hinged together 105 and to said plate.

10. In a type casting machine, the combination with a mold wheel having a plurality of openings, means to turn the wheel step by step to bring the openings in succession 110 to casting position, means to force metal through the selected opening in such a position, a matrix carrier movable across the face of the wheel to register its matrix with said opening, and means to clamp the carrier against the face of the wheel. 115

11. In a type casting machine, the combination with a mold wheel having a plurality of openings, means to turn the wheel step by step to bring the openings in succession to 120 casting position, means to force metal through the selected opening in such a position, a matrix carrier movable across the face of the wheel to register its matrix with said opening, and means to clamp the carrier against the face of the wheel, and means to eject the casting from said wheel at a succeeding position thereof. 125

12. In a type casting machine, the combination with a mold wheel having openings 130

through which metal may be forced, of a guideway beside said wheel, a matrix carrier slidable in said guideway across the face of the wheel, to register the matrix with 5 said opening, and a hinged clamp located in front of the wheel and adapted to clamp the matrix carrier against the same during the casting operation.

13. In a type casting machine, the combination with a mold wheel having openings through which metal may be forced, of a guideway beside said wheel, a matrix carrier slidable in said guideway across the face of the wheel, to register the matrix 10 with said opening, and a hinged clamp located in front of the wheel and adapted to clamp the matrix carrier against the same during the casting operation, said clamp being provided with a rear cross bar extending 15 behind the matrix carriers and adapted to detach the same from the wheel when the clamp is opened.

14. In a type casting machine, the combination with a mold wheel having an opening through which molten metal may be forced, of a matrix carrier movable to register the matrix with said opening, and a swinging clamp movable against the carrier to hold the same against the face of the 20 wheel, said clamp being provided with means to engage opposite side edges of the carrier and center the same with respect to 25 said opening.

15. In a type casting machine, the combination with a mold wheel having an opening through which molten metal may be forced, of a matrix carrier movable to register the matrix with said opening, and a swinging clamp movable against the carrier to hold the same against the face of the 30 wheel, said clamp being provided with means to engage opposite side edges of the carrier and center the same with respect to 35 said opening, said means comprising yielding side pieces with inclined edges, and inclined brackets beside the wheel and engageable with said side pieces when the clamp is closed, to force said pieces inwardly against the edges of the carrier.

50 16. A stick for type castings, comprising front and rear plates spaced apart, and an

intermediate plate slideable up and down, the front and intermediate plates having slots to receive the stems of the castings and being spaced from the rear plate, whereby 55 to confine the heads of the casting between the rear plate and the intermediate plate.

17. In a type casting machine, the combination of a mold wheel having a plurality of rows of openings arranged in succession 60 around the wheel, means to turn the wheel step by step to register an opening of each row in succession with casting mechanism, said wheel also having a series of spaced holes corresponding to the respective rows, 65 and a sliding pin movable into said holes successively, to lock and center the wheel in exact casting position.

18. In a type casting machine, the combination of a mold wheel having a plurality of 70 rows of openings arranged in succession around the wheel, means to turn the wheel step by step to register an opening of each row in succession with casting mechanism, said wheel also having a series of spaced 75 holes corresponding to the respective rows, and a sliding pin movable into said holes successively, to lock and center the wheel in exact casting position, and a plurality of ejecting pins corresponding to the holes of 80 each row and movable into the same to eject the casting.

19. In a type casting machine, the combination with a mold wheel having an opening through the same, through which metal 85 may be forced, of a hanger plate, two chains of matrix carriers hung from said plate, means to move the plate to shift the matrix carriers across the face of the wheel to register a selected matrix with said opening, 90 a swinging clamp movable against the carriers to clamp the same against the wheel, and an index finger engageable between the two chains of matrix carriers, to properly space the same apart. 95

In testimony whereof, I do affix my signature in presence of two witnesses.

EDWARD E. WILSON.
